UNITED STATES PATENT OFFICE.

JOSEPH SLEPIAN, OF WILKINSBURG, PENNSYLVANIA, ASSIGNOR TO WESTINGHOUSE ELECTRIC & MANUFACTURING COMPANY, A CORPORATION OF PENNSYLVANIA.

MAGNETIC AMPLIFIER AND SELF-MODULATOR.

Application filed April 21, 1921. Serial No. 463,208.

My invention relates to wireless systems and more especially to electrical systems which may be employed either to amplify or to modulate the variable currents employed in wireless telegraph or telephone systems.

One object of my invention is to provide an amplifying system which is not limited to the amplification of relatively small amounts of power by reason of inherent limitations in the design thereof.

Another object of my invention is to provide simple and efficient means whereby the undamped oscillations in sustained current-transmitting systems may be periodically modulated to admit of their reception by receiving stations which are unable to receive undamped signals.

Other objects will be apparent from the following description, taken in connection with the accompanying drawings.

Heretofore, in systems of amplification, it has been possible to amplify only relatively small amounts of power by reason of structural and theoretical limitations in the amplifying devices employed.

Furthermore, in the art of signaling, it has been customary, in stations employing sustained oscillating currents, to communicate with receiving stations unable to receive the undamped signals radiated therefrom by employing a special spark transmitter.

According to my invention, I provide an electrical system which may be employed, with slight modifications in the design thereof, either as an amplifier system for amplifying large amounts of power or as a self-modulating system for producing audible-frequency beats or groups of radiated waves in continuous-wave, wireless-transmission systems.

In my co-pending application, Serial No. 463,209, filed April 21, 1921, I have shown a purely electromagnetic system for accomplishing the desired results. In the application just mentioned, the system comprises a circuit having radio-frequency currents therein and a magnetizing winding, a circuit having audio-frequency currents therein and a magnetizing winding, a common magnetizable core member associated with said magnetizing windings, reactance devices resonant to said radio-frequency currents included in said first-named circuit

for causing the modulations of the radio-frequency currents to lag the modulating audio-frequency currents.

In the system just described, it was found that, if the losses in the audio-frequency circuit were sufficiently small, the effect of the lag between the modulations of the radio-frequency circuit and the modulating audio-frequency circuit is to cause a transfer of energy from the radio-frequency circuit to the audio-frequency circuit tending to maintain the currents in the latter circuit without additional audio-input. Thus, the system may easily become self-modulating.

It was further found that if the system were so adjusted that it was on the point of sustaining the currents in the audio-frequency circuit, small changes in the value of the audio-input effect relatively large changes in the value of the radio-frequency currents.

I have found, however, that the desired results heretofore mentioned may also be obtained by employing a mechanical movable armature member which is disposed between two small electromagnets; one of which is excited by the audio-frequency currents and the other of which is excited by the radio-frequency currents.

My invention may best be understood by reference to the accompanying drawings, in which:

Fig. 1 is a diagrammatic view of circuits and apparatus embodying my invention.

Figs. 2, 3 and 4 are curve diagrams illustrating the fact that, with the radio-frequency circuit in a nonresonant state, substantially no mechanical work is done by the force upon the armature due to the radio-frequency currents.

Fig. 5 is a curve diagram illustrating the fact that, with the radio-frequency circuit resonant to the radio-frequency currents therein, the currents just mentioned will do mechanical work upon the armature tending to sustain its motion.

Referring to Fig. 1, a radio-frequency circuit 1 is operatively connected to a local source of radio-frequency currents 2 through coupling coils 3 and 4, and to an audio-frequency circuit 5 through a magnetic device 6.

The source of energy 2 is shown comprising an arc 7, which is shunted by the cou-

pling coil 4 and a condenser 8. It is understood, however, that my invention is not to be limited to the particular type of oscillation generator shown in the drawings, as other sources of radio-frequency or ultra-audio-frequency currents may be employed.

The magnetic device 6 includes a pair of magnetizable members 12 and 13 carrying windings 9 and 11, respectively, which are included, respectively, in the radio-frequency circuit 1 and in the audio-frequency circuit 5. Flexibly mounted between the magnetizable members 12 and 13 is an armature member 14 which may be secured to a supporting member 15 by means of a flexible member or spring 16, and is so disposed between the magnetizable members 12 and 13 that it may periodically vary the self-inductance of the coil 9. The natural period of the spring 16, with the armature 14 attached thereto, is preferably resonant to the frequency of the audio-frequency currents in circuit 1.

The audio-frequency circuit 5 may comprise one or more of the following elements: a source of audio-frequency, such as a detector device for incoming signals (not shown); a coupling coil 17, which is associated with a pair of feed-back coils 18 and 19 hereinafter mentioned; and an inductance coil 21 and a condenser 22 for tuning the circuit to the audio-frequency currents.

The radio-frequency circuit 1 is shown as comprising the coupling coil 3, the winding 9, an inductance coil 23 and a condenser 24 for tuning the circuit to resonance with the source of energy 2; and a pair of rectifier circuits 25 and 26 which are connected in shunt to each other and in series relation in the circuit 1. The rectifier circuits 25 and 26 include, respectively, indicating devices 29 and 31, shown as a pair of telephone receivers and the oppositely connected rectifiers 27 and 28. The indicating devices 29 and 31 may be shunted also by the feed-back coils 18 and 19, which are connected in opposition, as shown.

The magnetizable members 12 and 13 are preferably operated upon the linear portion of the magnetization curve.

The curve diagrams shown in Figs. 2, 3 and 4 explain the fact that, if the radio-frequency circuit 1 were non-resonant to the source of energy 2, the modulation of the currents therein by the audio-frequency currents would be effected with just sufficient power input in the audio-frequency circuit to supply the energy losses in the magnetic device 6.

Fig. 2 is a curve diagram showing the variations in the air-gap length of the magnetizable member 14, with respect to the magnetizable member 12; and, for purposes of illustration, has been represented in the sine-wave form.

Fig. 3 is curve diagram showing the modulations of the radio-frequency currents produced by the audible-frequency variations in the reluctance of the magnetic path through the armature member 14 and the magnetizable member 12. In the last-mentioned diagram, curve 32 represents the radio-frequency oscillations, and curve 33 represents the audio-frequency modulation thereof. Neglecting the slight lag, equal to a small fraction of the radio-frequency period, which would be caused by hysteresis, it is evident that the mean pull upon the armature 14, that is caused by the radio-frequency currents is in phase with the modulations 33, and it has been so illustrated in Fig. 4.

From the foregoing curve diagrams, it may readily be seen that the curve representing the mean pull upon armature 14 is in phase with the curve representing the variations in the air-gap length, and, therefore, in quadrature with the velocity of the armature. Hence, no mechanical work is done by the radio-frequency currents upon the magnetic device 6 under the conditions assumed. The audio-input, therefore, is required to supply only the losses in the magnetic device 6, in order to modulate the radio-frequency currents.

I have found that, by adding a series-resonant device, such as that indicated at 23, 24, tuned to resonance with the radio-frequency currents, the modulations of the radio-frequency currents are caused to lag behind the modulating audio-frequency currents, as indicated in the curve diagram shown in Fig. 5.

The reason for the lag produced by the addition of the series-resonant reactance device will probably be best understood by a consideration of the energy stored by the device. If an oscillatory electromotive force of constant amplitude is suddenly impressed upon an oscillatory circuit containing a series-resonant device, the currents will not immediately reach a steady value, since the energy stored in the resonant device must be supplied from the source; but the amplitude of the oscillations will gradually increase for a number of cycles, dependent upon the ratio of the stored energy to the resistance load, as is well known. Similarly if the oscillatory electromotive force is decreased in amplitude, or withdrawn altogether, the excess energy stored in the reactance devices will cause the corresponding modulation of the currents to be postponed to a time which may be a number of cycles later.

The result of such lag in the present device is that the modulations have a component in phase with the movements of the armature, as well as a component displaced 90° thereupon. It will be seen that the first-mentioned component tends to maintain the movements of the armature, and that energy

is thus supplied to the audio-frequency circuit from the radio-frequency circuit, tending to reduce the necessary audio input.

By sufficiently reducing the losses in the audio-frequency circuit, enough power may be supplied thereto from the radio-frequency circuit to maintain the currents therein without additional audio-frequency input. The system then becomes a self-modulator.

10 I have found that my system is most efficient as an amplifier upon the adjustment of the inductance coil 23 and the condenser 24 to such value that the system is on the point of sustaining currents in circuit 5. Additional amplification may be obtained through the feed-back coils 18 and 19 and the coupling coil 17, said coils feeding back the audio-frequency modulation of the currents in the radio-frequency circuit 1.

20 Assuming radio-frequency currents supplied to the radio-frequency circuit 1 by means of the source of radio-frequency energy 2, the effect of impressing currents of an audible frequency upon circuit 5 is to effect the modulation of the radio-frequency currents in circuit 1 at frequencies corresponding to those in the audio-frequency circuit 5, all as hereinbefore described.

The effect of the rectifiers 27 and 28 is to 30 render audible, in the indicating devices 29 and 31, the note corresponding to that of the audio-frequency modulations.

The self-modulating characteristic of my system is of particular importance in marine work in that it eliminates the spark transmitters which have heretofore been considered necessary in continuous-wave systems when desiring to communicate with receiving systems responsive only to energy 40 radiated by spark transmitters.

Another advantage of my invention resides in the fact that it embodies means whereby reception of signal impulses may be effected from continuous wave systems 45 without heterodyning the received energy.

Still another advantage of my invention resides in the provision of a magnetic amplifying system wherein relatively small or large amounts of power may be efficiently 50 amplified.

While I have shown only one embodiment of my invention, in which the inductance of a circuit is mechanically varied, it is obvious that a mechanically varied condenser may be 55 equally as well employed without departing from the spirit and scope of my invention. I desire, therefore, that only such limitations shall be imposed thereon as are set forth in the appended claims.

60 I claim as my invention:

1. In a magnetic amplifier, a circuit having radio-frequency currents therein and a magnetizing winding, a second circuit having audio-frequency currents therein and a magnetizing winding, a magnetizable mem-

ber so disposed that the resultant motion thereof causes changes in the inductance of the radio-frequency circuits, whereby the radio-frequency currents may be modulated at frequencies corresponding to the audio- 70 frequency currents.

2. In a magnetic amplifier, a circuit having sustained oscillating currents therein and a magnetizing winding, a circuit having audio-frequency currents therein and a magnetizing winding, a magnetizable member adapted to respond to the magnetic fields set up by currents in said magnetizing windings, whereby the currents in said first-named circuit may be modulated at frequencies corresponding to those in said second-named circuit. 75

3. In a magnetic amplifier, a circuit having sustained oscillating currents therein and a magnetizing winding, a second circuit having audio-frequency currents therein and a magnetizing winding, magnetizable members for each magnetizing winding, and a vibratory magnetizable member disposed adjacent said first and second-named magnetizable members. 80

4. In a magnetic amplifier, a circuit having sustained oscillating currents therein and a magnetizing winding, a second circuit having audio-frequency currents therein and a magnetizing winding, magnetizable members for each magnetizing winding, an armature responsive to the magnetic fields set up by currents in said first and second-named magnetizing windings, whereby said oscillating currents are modulated in accordance with said audio-frequency currents and means for causing the modulations of said oscillating currents to have such phase relation to said audio-frequency currents that 90 the mean pull of said modulated currents on said armature has a component in phase with the movement thereof. 100

5. In a magnetic amplifier, a resonant circuit having radio-frequency currents therein and a magnetizing winding, a circuit having audio-frequency currents therein and a magnetizing winding, magnetizable members for each magnetizing winding and a flexibly mounted magnetizable member responsive to the magnetic fields set up by currents in said magnetizable members, the resultant motion of said flexibly mounted magnetizable member being such that the movement thereof is approximately in phase with the force thereon caused by said radio-frequency currents. 110

6. In a magnetic amplifier, a circuit carrying audio-frequency currents therein and including a magnetizing winding and a coupling coil, a circuit carrying radio-frequency currents therein and including a magnetizing winding, a pair of rectifiers connected in parallel opposition, an indicating device and feed-back coils associated 120

- with said coupling coil, magnetizable members associated with each magnetizing winding, and a flexibly mounted magnetizable member so disposed adjacent said magnetizing windings that the resultant motion thereof effects the modulation of said radio-frequency currents at a frequency corresponding to the audio-frequency currents.
7. The combination with a source of sustained oscillations, of a magnetizing coil connected thereto, a vibratory armature associated with said coil, whereby the reactance of the latter is varied in accordance with the movements of said armature, said armature having a natural period of vibration different from that of said oscillations, and means for retarding the modulations in the amplitude of said oscillations with respect to said variations in reactance.
8. The combination with an oscillatory circuit including substantially resonant inductance and capacitance devices, of a movable member associated with one of said devices for varying the reactance thereof, said member having a natural period of vibration differing from that of said resonant devices.
9. A magnetic amplifier comprising a circuit having sustained oscillating currents therein, a second circuit having audio-frequency currents therein, means controlled by said audio-frequency currents for mechanically varying the reactance of said first-named circuit to cause corresponding modulations of the currents therein, and auxiliary means for transferring audio-frequency power from said first-named circuit to said second-named circuit.
10. A magnetic amplifier comprising a circuit having sustained oscillating currents therein, a second circuit having audio-frequency currents therein, means controlled by said audio-frequency currents for mechan-

ically varying the reactance of said first-named circuit to cause corresponding modulations of the currents therein, a rectifier for said oscillating currents, and means for transferring audio-frequency power from said rectifier currents to said audio-frequency circuit.

11. The method of varying the reactance of a sustained oscillatory-current circuit by means of a tuned vibratory member, which consists in so varying the phase relationship between the variations in said reactance and the resultant modulations in said oscillatory current that said modulations have a component in phase with the velocity of said vibratory member.

12. In a carrier-current signaling system, the combination with a carrier-current circuit thereof, of modulating means comprising an inductance device included in said circuit, a second circuit having audio-frequency currents therein, and movable means controlled by said audio-frequency currents for mechanically varying the reactance of said inductance device to cause corresponding modulations of the currents in said first-named circuit.

13. In a carrier-current signaling system, the combination with a carrier-current circuit thereof, of modulating means comprising a magnetizable-core inductance device included in said circuit, a movable magnetizable armature included in the magnetic circuit of said inductance device, and means for moving said armature in such manner as to vary the inductance of said device in response to a signal or signals to be transmitted.

In testimony whereof, I have hereunto subscribed my name this 14th day of April, 1921.

JOSEPH SLEPIAN.
